TRANSLUCENT CEILING PANEL

David G. Hills, Hartford, Conn., assignor to Plax Corporation, West Hartford, Conn., a corporation of Delaware

Application May 20, 1954, Serial No. 30,590

Term of patent 14 years

(Cl. D48—23)

FIG. 1

FIG. 2

FIG. 3

FIG. 4

Fig. 1 is a top plan view of a translucent ceiling panel, showing my new design;

Fig. 2 is a side elevation view of the panel;

Fig. 3 is an enlarged cross-sectional view of half of the panel taken on line 3—3 of Fig. 1; and

Fig. 4 is an enlarged cross-sectional view of a portion of the panel taken on line 4—4 of Fig. 1.

I claim:

The ornamental design for a translucent ceiling panel, substantially as shown.
